To all whom it may concern:

Be it known that I, Edward A. Bittel, a citizen of the United States, residing at Rochester, in the county of Monroe and State of New York, have invented a new, original, and ornamental Design for Flower Baskets, of which the following is a specification, reference being had to the accompanying drawing, forming part thereof.

In the drawing:

I claim:

The ornamental design for a flower basket, as shown.

EDWARD A. BITTEL.
